UNITED STATES PATENT OFFICE.

HARRY W. McDONALD, OF MINNEAPOLIS, MINNESOTA, ASSIGNOR TO CEDAR CREEK
OIL & GAS CO., OF FARIBAULT, MINNESOTA, A CORPORATION OF DELAWARE.

WELL-DRILLING TOOL.

Application filed July 15, 1925. Serial No. 43,810.

This invention relates to new and useful improvements in drilling tools of the cable supported or impact type and more particularly relates to means adapted for use in connection with such tools whereby they may be adapted for the mud-laden fluid method of drilling oil wells, which employs a mud-laden fluid delivered under pressure, at the bit or drilling end of the tool. This fluid functions to wash or flush the cuttings and slush from the bored hole and also to seal the walls thereof to prevent water, gases, and the like, from entering the well; which might otherwise enter the bored hole or well under pressure and cause serious damage thereto, resulting frequently in the interruption of further work of drilling in the well and therefore the loss of the well, and possibly the drill tools positioned therein. The mud-laden fluid method of drilling oil wells is rapidly increasing in popularity as a result of the substantial elimination of fire hazards and other dangers commonly prevalent with the use of ordinary standard tools, such as the rotary type or the cable type, employing a brazier or bucket for removing the cuttings from the bored hole. Difficulties have been encountered, however, in using the mud-laden fluid method of drilling, especially when drilling deep wells or holes, caused usually, by the difficulty experienced in withdrawing the tools from the hole for repairs or sharpening, as a result of the excessive weight of the supporting means, and the present method employed for delivering the fluid to the tool. It is, therefore, desirable that means be provided whereby water under pressure may be delivered at the point of the tool regardless of the depth at which the tool is operated, and independently of the tool-supporting means and also that means be provided whereby the drill cable will be retained in its normal wound condition, thereby maintaining its normal tensile strength with a resultant increase in the effective operating life of the cable.

The novel drill tool featured in this invention includes a rope socket, jar-bar (so called) and drill stem, to the lower end of which the drilling tool or bit is demountably connected. This tool is particularly designed to meet the above requirements, and employs a flexible drill-supporting cable having one end secured to the rope socket of the drilling

tool and its other end passed through the feeding mechanism mounted upon the usual walking beam of the drilling machine, the surplus cable being wound upon a drum mounted upon the drilling apparatus and adapted to feed the cable therefrom in the usual manner. A flexible steel water line or hose is employed to deliver the mud-laden fluid under pressure to the bit or drilling end of the tool. This flexible water line is independent of the tool-supporting means and is engaged by the walking beam and is mounted upon a drum rotatably mounted upon the drilling machine, and a source of water supply is connected therewith for supplying water under pressure to the steel hose line.

Means are also provided in the rope socket to retain the drill-supporting cable in its normal twisted condition, thereby eliminating any tendency to partially untwist as a result of the weight and rotation of the drill tool and also as a result of a portion of its own weight being suspended therefrom, which untwisting is a common occurrence, especially when drilling very deep wells or holes.

The particular object of the invention, therefore, is to provide an improved drilling tool particularly adapted for use with the mud-laden fluid method of drilling, with a cable-supported or impact tool, and having the water line supplying fluid to the tool with the line supported independently of the tool-supporting member.

Other objects of the invention will appear from the following description and will be more specifically pointed out in the annexed claims.

In the drawings there has been disclosed a structure designed to carry out the various objects of the invention, but it is to be understood that the invention is not confined to the exact features shown as various changes may be made within the scope of the claims which follow.

In the accompanying drawings forming part of this specification,

Figure 1 is a sectional view of a typical oil well, showing a drilling tool positioned therein with the invention applied thereto;

Figure 2 is an enlarged detail view of the rope socket and the upper end of the jar-bar;

Figure 3 is an enlarged sectional view

of the jar-bar showing the general construction thereof;

Figure 4 is an elevational view of the jar-bar showing the means provided thereon 5 for rotating it when in operation;

Figure 5 is a cross sectional view on the line 5-5 of Figure 4;

Figure 6 is a similar view on the line 6-6 10 of Figure 4;

Figure 7 is an enlarged detail sectional view of the rope socket showing how the ropes are seated therein;

Figure 8 is a cross sectional view on the line 8-8 of Figure 7;

Figure 9 is a detail view of the drill stem showing how the steel water line is slidably connected thereto;

Figure 10 is a modified form showing the use of a non-flexible steel water line used 20 in connection with the improved jar-bar and rope socket;

Figure 11 is a cross sectional view on the line 11-11 of Figure 10;

Figure 12 is a similar view on the line 25 12-12 of Figure 10 showing how the steel water line is slidably connected to the rope socket;

Figure 13 is a view illustrating a modified jar-bar;

Figure 14 is a view illustrating the drill tool at the lower end of the drill stem and also showing the steel water line therein;

Figure 15 is a view showing how the lower 35 end of the steel water line may be projected through the drill tool to prevent the discharge opening therein from becoming clogged;

Figure 16 is a detail view of a portion of 40 the steel water line to show how the sections are detachably connected together;

Figure 17 is a diagrammatic view illustrating how the non-flexible steel water line is used in the drilling of a well; and

Figure 18 is a similar view showing the 45 steel water line suspended in the well and the drill tool removed therefrom.

In the selected embodiment of the invention here shown, there is illustrated, for purposes of disclosure, a vertical sectional view of a typical oil well showing the novel drilling tool positioned therein and also illustrating the different formations of the earth through which the drilling tool must penetrate before striking the desired oil sand.

The means provided for securing the drill-supporting cable to the tool, is commonly termed the rope socket, and consists of a cylindrical shell 21 having a bore 22 60 therein adapted to receive a stem 23 provided with an enlarged portion 24 seated in a relatively larger bore 25 in the lower portion of the shell 21. An annular shoulder or seat is provided between the bores 22 and 25, which is grooved to receive a plu-

rality of suitable balls or rollers 26, functioning as a thrust bearing to carry the weight of the drill tool. The stem 23 is provided with a bore 27 adapted to receive the lower end of the drill cable 28. The lower portion of the stem 23 has a relatively larger bore 29 in which the end of the cable 28 is inserted, after which the bore 29 is preferably completely filled with molten lead or babbitt as shown, to fixedly secure the cable to the stem 23. The enlarged portion 24 of the stem 23, therefore, functions as a head to support the shell 21 to which the jar-bar and drill are connected. The upper end of the stem 23 is preferably threaded 75 to receive a cap 31, which functions to retain the shell 21 in proper position upon the stem 23. The adjacent or abutting faces of the cap 31 and shell 21 are grooved to receive a suitable packing 32 to prevent the mud-laden fluid or grit from entering the bearing between the stem 23 and the shell 21. A grease plug and duct 33 is preferably provided in the shell 21 to provide means for lubricating the bearing between the shell 21 and the stem 23.

The lower end of the enlarged bore 25 of the shell 21 is also threaded to receive a plug 34 which is provided with a plurality of apertures 35 adapted to receive the cables 36 connecting the rope socket with the upper end of the jar-bar. Each aperture 35 is provided with an enlarged bore 37 at its upper end, in which the upper end of the connecting cables 36 are inserted and the bores 37 filled with molten lead or babbitt to secure the cables to the plug 34. The rope socket will, therefore, provide a swivel joint between the jar-bar and the drill-supporting cable 28, so that the jar-bar and cable 28 may relatively rotate without interference.

The lower ends of the cables 36 connecting the rope socket with the upper end of the jar-bar are similarly connected to a cylindrical member 38 having its lower end threaded to receive a tubular member 39 having an enlarged portion or head 41 slidably seated in a bore 42 of the member 43, which is threaded to receive a threaded extension 44 of a complementary base member 45 as shown in Figure 3. The tubular member 39 is slidably mounted in a relatively smaller bore 46, provided in the upper end of the member 43, and a stuffing box 47, of ordinary construction, is provided to exclude the mud-laden fluid from the bore 42 and 46 of the upper member 43. The members 43 and 45 are provided with spirals 48 which are so arranged as to counteract the twisting action of the drill cable when the drill tool is being operated. The spirals also tend to rotate the tool during the drilling operation caused by the upward flow of the mud-laden fluid or water thereagainst. In actual operation it has also been found that the 125 130

spirals tend to throw the mud-laden fluid outwardly against the walls of the bored hole thereby more tightly sealing the walls against high gas and water pressures.

6 The means provided for connecting the drill-stem 49 to the lower end of the jar-bar is shown in Figures 3 and 4. As here shown a sleeve 51, having a bore 52 therein, is rotatably secured to the lower end of the 10 base member 45 of the jar-bar by means of a member 53 having an enlarged head 54 seated in the bore 52 of the sleeve 51. The upper end of the member 53 is mounted in a threaded socket 55 provided in the base 15 member 45. The shoulder 56 of the head 54 is adapted to cooperate with a similar shoulder in the sleeve 52 to provide a thrust bearing adapted to carry the weight of the drill-stem. Suitable balls or rollers 57 may be 20 provided between these shoulders to minimize friction therebetween. A packing 58 is mounted in grooves provided in the lower face of the base member 45 of the jar-bar and the upper face of the sleeve 51, to prevent 25 the mud-laden fluid and other foreign material from entering the bearing surfaces between the member 53 and sleeve 51. A threaded plug 59 is mounted in the lower end of the sleeve 51 and is provided with a tapered thread 61 adapted to receive one end 30 of the drill-stem 49 as shown in Figure 9. In the operation of drilling a hole, the swivel joint connection between the drill-stem and the jar-bar will tend to limit the 35 rotation of the drill-stem, and therefore the tool, at each impact stroke of the drill-stem. If desired, however, the swivel joint between the drill-stem and the jar-bar may be dispensed with and the drill-stem connected 40 directly on to the lower end of the base member 45 of the jar-bar.

Another feature of this invention resides in a novel mounting and arrangement of the metal water line or pipe within the drill tool. Referring particularly to Figures 3 and 9, it will be noted that the cylindrical member 38 and also the tubular member 39 are provided with aligned bores or apertures adapted to receive a pipe section 62 which 45 is slidably mounted therein. This pipe section also extends through the head 41, base member 45 of the jar-bar, through the member 53 of the universal joint beneath the member 45, and through the plug 59 into an enlarged bore 63 provided in the drill-stem 49. The upper end-portion of the drill-stem, however, is provided with a relatively smaller bore 64 to provide an annular shoulder 65 adapted to be engaged by a head 66 formed in the lower end of the pipe section 62. The head 66 is securely mounted upon the pipe section 62 and functions to prevent the pipe section from accidentally being withdrawn from the drill-stem while 55 the tool is in operation. The enlarged socket 60 or bore 63 in the drill-stem extends substantially the full length of the stem and has its lower end in alignment with a duct or passage 67 provided in the drill head or bit 68, as shown in dotted lines in Figure 9. 70 An important feature of this invention resides in the novel method employed for delivering the water or mud-laden fluid to the tool while in operation. The method most commonly employed to deliver the water or 75 fluid to a drill tool of the impact type, such as here shown, is to provide a duct in the drill stem or tool-supporting means having, a connection with a source of supply above the ground level. This method of supplying the fluid to the tool has been found more or less objectionable as a result of the difficulties experienced when withdrawing the tool from the well, owing to the excessive 80 weight of the drill stem, especially when operating in deep wells. Such hollow drill stems usually comprise a plurality of sections suitably secured or coupled together for operation as a unit. The joints or couplings between these sections have been 85 found a source of trouble, as it frequently occurs that the sections become disconnected from one another, after which considerable time may be lost before they can again be 90 coupled together. It is sometimes necessary to remove the disconnected sections from the well before they can again be connected and 95 operation resumed. In the novel structure here shown, the fluid is delivered to the tool by means of a flexible water line or hose 69 supported independently of the tool-supporting means. The lower end of this water line is connected to the upper end of the pipe connection 62 by means of a coupling 100 71 (see Figure 3). By thus supporting the 105 water line independently of the drill-supporting means, the tool may be supported upon and operated by the flexible cable 28, thereby dispensing with heavy hollow piping as tool-supporting and water delivery 110 means which must necessarily be employed when the fluid is delivered, as above described.

In the operation of this novel drilling tool, the rope socket, jar-bar and drill-stem, including the drill-head or bit, are connected together as shown in Figure 1, after which the tool, as a whole, is sunk or drilled into the ground by impacting therewith, which is a common well-known operation in well 115 drilling machinery. The upper end of the cable 28 is usually mounted upon the upper end of an oscillating beam, which is operated from the drilling machine to raise or lift the drill tool and allow it to drop by gravity against the bottom of the hole, thereby causing the cutting end or bit of the tool to cut away or loosen the material with which it contacts. During such operation of 120 the tool, a stream of water or a mud-laden 125 130

fluid is delivered under pressure to the cutting end of the tool through the pipe connection 62, and the water line 69 connected to the upper end of the pipe section. The upper end of the flexible water line 69 is also usually connected with the oscillating beam and is mounted upon a drum carried by the drilling machine and having means for supplying water thereto. As a result of the swivel joint provided in the rope socket, and also the spirals 48 in the members 43 and 45 of the jar-bar, the tendency of the tool-supporting cable to partially unwind will be eliminated, thereby also preventing the water line from becoming twisted with the tool-supporting cable during the drilling operation. Should the lower end of the tool accidentally become stuck or lodged in the bottom of the hole or well the head 41 of the stem 39 may be relatively lowered into the lower portion of the enlarged bore 42, after which a sudden upward pull may be exerted thereon by means of the tool supporting cable, thereby causing the head 41 to be thrust against the annular shoulder 72 and the member 43 with a resultant loosening of the drill-stem and tool so that the tool as a whole may be withdrawn from the well. When operating under normal conditions the head 41 will always be in the position shown in Figure 3 wherein the lower portion of the jar-bar and the drill-stem and supporting means will be carried entirely upon the shoulder 72 of the head 41. The connection of the water line 62 with the drill-stem is also such as to permit it to relatively move therein as may be seen by reference to Figure 9. Thus, the drill-stem and its supporting means may be rotated without affecting the operation of the water line mounted therein.

The lower end of the plug 34 of the rope socket is preferably provided with a notch 73 in which the water line 69 may be seated as particularly shown in Figure 8, thereby eliminating the danger of the water line being unnecessarily bent during the drilling operation of the tool.

By the use of this novel drilling tool in connection with the mud-laden method of drilling, the well or hole may be bored the necessary or desired depth without the necessity of inserting linings or casings therein until after the well has been completed. During the drilling operation the mud-laden fluid or water, delivered under pressure at the cutting end of the tool, will wash or flush the cuttings from the hole as the water will rise in the hole until it reaches the top thereof where it may be directed into a suitable receiving means (not shown). Such upward flow of the mud-laden fluid in the bored hole will thoroughly seal the walls

thereof against inward pressures caused by encountering gas pockets or oil and water bearing sands through which it is desired to drill, as shown in Figure 1. The weight of the column of water in the well will also exert an outward pressure against the walls of the well thereby preventing gas or water from entering the well during the process of drilling.

After the well or hole has been drilled the desired depth the drill tool may readily and conveniently be removed therefrom by the usual drilling apparatus (not shown), after which a casing or lining 74 is inserted therein while the well is still filled with the mud-laden fluid. The mud-laden fluid may then be pumped from the well until it has been entirely removed therefrom as shown, on the right hand side of Figure 1, or, until the water pressure within the bored hole is overcome by the oil or gas pressure, after which the oil or gas will flow upwardly through the casing to the top of the well. The above condition, of course, is true only when encountering oil sands having a high pressure or in the case of gas pockets.

The novel rope-socket, jar-bar and drill-stem, and also the independent means for supplying water to the tool as a whole, is, therefore, particularly adapted for use with the mud-laden fluid method of drilling. By slidably mounting the water line in the drill-stem, as above described, the mud-laden fluid or water may be delivered under pressure at the point of the tool without any difficulty. Also as a result of the swivel joint provided in the rope socket and the spirals 48 provided in the jar-bar, the tool-supporting cable will be prevented from partially unwinding and the tool will also be automatically rotated at each impact stroke.

Figures 10 to 18, inclusive, illustrate a similar tool employing a non-flexible water line which extends from the drill-stem to the usual derrick mounted over the bored hole or well as shown in Figures 17 and 18.

In the construction here shown the rope socket comprises an upper portion 75 and a lower portion 76 secured together by means of a threaded connection 77. The drill-supporting cable 28 is rigidly secured to the upper portion 75 of the rope socket and the cables 36 are suitably secured to the lower portion 76 thereof, and depend therefrom and have their lower ends secured to the tubular member 38 in a manner similar to that shown and described with reference to the previous figures. The jar-bar is similar in construction to that shown in Figure 3, but instead of being provided with a swivel joint between the base member 45 thereof, and the drill-stem 49, the latter is provided with a reduced extension 79 adapted to be connected to the drill stem 49 by means of a

threaded connection 81 as shown. The drill stem may be constructed of a plurality of sections as shown in Figure 14.

A feature of the construction here shown resides in the novel mounting in the drill stem of the water line or pipe section 82 by which water is supplied under pressure at the cutting end of the drill tool. By reference to Figure 15 it will be noted that the pipe section 82 is adapted to project beyond the cutting end 83 of the drill when the drill stem is raised to the position shown in the above figure. When the drill stem is dropped by gravity against the bottom of the well, the lower end of the pipe section 82 will enter the drill stem as it is normally suspended in the position shown during the operation of the drilling tool. By thus allowing the pipe 82 to project beyond the cutting face 83 of the tool each time the drill stem is moved upwardly the water discharge opening at the bottom of the tool will be maintained open and therefore cannot become clogged to prevent the delivery of water therethrough.

Figures 17 and 18 illustrate the operation of drilling a well employing a non-flexible water line to deliver water under pressure to the cutting end of the tool. This non-flexible water line is also supported independently of the tool-supporting means. In the form here shown the water line or pipe 82 which is constructed of a plurality of sections as indicated in Figure 16 will extend from a point adjacent the bottom of the bored hole to a point above the ground level as shown in Figure 17. A suitable connection 84 is secured to the upper end of the pipe 82 and has a cable 85 connected thereto, which upwardly passes therefrom over a sheave 86 from which it passes downwardly to a suitable winding drum or other supporting means provided on the drilling machine 87, partially shown in the figure. The connection 84 is also provided with an intake 88 having a hose connection 89 connected thereto, which has its opposite end connected to a suitable source of water supply adapted to supply water thereto under pressure. When it is desired to remove the drill tool from the well the tool will be raised out of the well as shown in Figure 18, after which a suitable clamp 91 is secured to the upper end of the pipe 82 to prevent the portion of the pipe extending into the well from dropping therein when the pipe sections are disconnected above the clamp as shown. When two of the pipe sections 82 have thus been disconnected the tool may readily be removed from the pipe sections 82 suspended from the connection 84 as shown.

Thus it will be seen that the water delivery conduit is separately mounted, suspended and manipulated; that said conduit is adjustable longitudinally of the tool, passes

through the tool; and that its delivery end is maintained at a level above that of the bottom of the well, (see Figures 14-15), a distance less than the length of the reciprocatory drilling movement, so that it projects below the drill when the drill is at its upper reciprocatory limit, thus acting to clean the drill bore.

Having thus described my invention what I claim as new and desire to secure by Letters Patent is:

1. A device of the class described including a jar-bar, drill stem and drill head separately flexibly supported, and an independently supported mud-laden-fluid delivery conduit, connecting with and extending through said jar-bar, drill stem and drill head.

2. A device of the class described including a jar-bar, drill stem and drill head separately flexibly supported, and an independently supported mud-laden-fluid delivery conduit, connecting with and slidably extending through said jar-bar, drill stem and drill head.

3. A device of the class described including a jar-bar, drill stem and drill head separately flexibly supported, and an independently supported mud-laden-fluid delivery conduit connecting with and extending through said jar-bar, drill stem and drill head, upon which conduit the drill head reciprocates during the drilling operation whereby the bore of the tool is cleaned and mud-laden-fluid delivery connection is maintained below the drill head.

4. In a device of the class described, including a jar-bar, drill stem and drill head separately flexibly supported, and an independently supported non-flexible water supply pipe slidable through said jar-bar, drill stem and drill head, with the lower end of the pipe adapted to project beyond the cutting face of the drill head as the same is moved upwardly, and further adapted to clean the bore of said head and maintain delivery connection therebelow.

5. A well drilling tool comprising a jar-bar, a drill stem, and a drill head, a conduit slidable through said jar-bar, stem, and head, and means exteriorly of the bar adapted to rotate the same about said conduit when moved downwardly in a bored hole, as a result of the flow of fluid against said means.

6. A well drilling tool comprising a jar-bar, a drill stem, and a drill head, a duct in said jar-bar, drill stem and head for delivering fluid to the cutting point of the head, and spirals on said jar-bar adapted to co-act with upward flowing fluid in the bored hole, to relatively rotate said jar-bar, drill stem and head.

7. A well-drilling tool including a jar-bar, a drill-stem and a drill head, a pipe

connection slidably mounted in said jar-bar and said drill-stem, and head, and having a connection with a supply source to deliver a mud-laden fluid under pressure at the 5 boring end of said head, for the purpose specified.

8. A well-drilling tool including a jar-bar, a drill-stem and drill head, a pipe connection slidably mounted in said jar-bar and 10 said drill-stem, and head, and having a connection with a source of fluid supply to deliver a mud-laden fluid under pressure at the boring end of said head for the purpose specified, and means on said pipe connection 15 to limit the longitudinal movement thereof.

9. A well-drilling tool comprising a rope socket, a jar-bar and flexible means connecting said rope socket and jar-bar to permit relative translative and rotary movement 20 between said socket and bar.

10. A well-drilling tool comprising a rope socket and a jar-bar and three flexible elements connected with said rope socket and jar-bar arranged in triangular formation.

25 11. A well-drilling tool including a rope socket and jar-bar, an inflexible water delivery pipe traversing said rope socket and jar-bar and flexible means connecting said

socket and bar for permitting independent translative and rotative movements of said 30 socket and bar upon and lengthwise of said inflexible conduit.

12. A well-drilling tool including a rope socket and a jar-bar, a supporting cable connected to said socket and adapted for rotary 35 movement therein, and flexible means connecting said socket with the jar-bar, said means comprising a plurality of flexible cables having means for connection with said socket and said jar-bar.

13. A well-drilling tool comprising a rope socket, a jar-bar and a drill-stem adapted to have a drill head connected thereto, a supporting cable connected to the rope socket, a duct in said jar-bar and said drill-stem 45 having means for connection with a supply line to deliver fluid under pressure at the cutting end of the head to discharge the loosened material from the bored hole and seal the walls thereof, and means in said rope socket and said drill-stem to prevent 50 partial unwinding of said supporting cable.

In witness whereof, I have hereunto set my hand this 10th day of July, 1925.

HARRY W. McDONALD.
